UNITED STATES PATENT OFFICE.

EDWARD J. CONDON, OF DIXON, ILLINOIS.

CEMENT-POST MACHINE.

1,094,642.

Specification of Letters Patent. Patented Apr. 28, 1914.

Application filed August 1, 1910. Serial No. 574,932.

To all whom it may concern:

Be it known that I, EDWARD J. CONDON, a citizen of the United States, residing at Dixon, in the county of Lee and State of Illinois, have invented certain new and useful Improvements in Cement-Post Machines, of which the following is a specification.

My invention pertains to concrete post machines, and aims to provide a simple and novel device whereby such posts can be rapidly and cheaply produced.

In the manufacture of fence posts of the character mentioned it is usual to embody therein some reinforcing means, such as wires or rods, extending through the same, and it has been demonstrated in practice that to get the best results such reinforcing means must be located in a particular position in the post.

In my invention I provide a mold, and means for filling the same by two or more operations, the locating of the reinforcing means being accomplished between the operations, the amount of material delivered to the mold by each operation being predetermined, and capable of being increased or diminished, as desired.

In the accompanying drawings: Figure 1 is a plan view of my invention. Fig. 2 is a front elevation thereof. Fig. 3 is an end elevation thereof. Fig. 4 is a vertical cross-section, on the line $x-x$ of Fig. 1. Fig. 5 is a detail, showing one of the wedges 21.

Similar parts are indicated by corresponding figures of reference throughout the several views.

1 represents the frame of the machine, preferably constructed of metal, and to the rear part of which are pivotally attached end pieces 2, between which is secured a hopper or receptacle 3. At each end of the machine is a bar 4, upon which are supported cross-pieces 5 and 6, above which is supported a plate 7, such plate being also located just beneath the receptacle 3. Between the plate 7 and end-pieces 2 is slidably mounted a bar 8, the ends of which project beyond the end-pieces and are connected by links 9 with a pair of hand-levers 10, fulcrumed on brackets 11, fixed to the rear part of the frame 1. By the operation of the levers 10 the bar 8 can be moved forwardly or rearwardly, as desired.

Secured to the front face of the cross-piece 6 is a plurality of brackets 12, by means of bolts 13 passing through such

cross-piece and through vertical slots 14 in such brackets. Upon the brackets 12 is supported a pallet 15, of suitable shape, one edge of such pallet being in contact with the face of the cross-piece 6. The bars 4 are projected forwardly beyond the frame of the machine, and pivotally supported on such extensions is a front board 16, adapted to be swung upwardly against the outer face of the pallet 15. In such position the board 16 is held in place by means of notched arms 17, pivoted to the frame 1, and engaging plates 18 on the ends of the board 16. Upon the pallet 15 are supported end-pieces 19 and 20. The upper part of the cross-piece 6, pallet 15, front board 16, and blocks 19 and 20 comprise the mold in which the post is formed.

In operation, the material from which the posts are to be produced is placed in the receptacle 3 in a plastic condition, and the bar 8 moved rearwardly, permitting a portion of the material to pass downwardly upon the plate 7. The bar 8 is then moved forwardly, carrying the material which is between the lower end of the hopper and the plate 7 into the mold at the front of the machine. The bar is then again moved rearwardly, and the operation repeated until the mold has received the desired amount of material. Between certain of the filling operations the material in the mold is provided with suitable reinforcing means. For example, if it is deemed expedient to have such reinforcement located at a point which will equal one-fourth the thickness of the post, the first operation will fill the mold to one-fourth of its depth, whereupon the strengthening rods or wires will be placed therein. With two more operations the mold is filled to within one-fourth the distance to the top thereof, and additional wires are located therein, after which the mold is filled by one more movement of the bar 8, and the material in the mold subjected to a tamping process to form the same into a compact mass. In delivering the several quantities of material to the mold, due allowance must be made for the shrinkage thereof caused by the tamping operation.

It will be apparent that the amount of the mixture which is delivered to the mold by one operation of the bar 8 is determined by the movement of such bar, and that if the rearward movement of such bar is increased, the amount of material delivered will be

correspondingly increased, and vice versa. On account of the end-pieces 2 being pivoted near their rear ends, there is at all times a close contact between the lower edge 5 of the hopper and the bar 8, caused by the weight of the hopper and contents. This serves to keep the upper face of the bar 8 free from the material in its rearward and forward movement. So that the friction between such parts will not be sufficient to interfere with the working thereof, however, wedges 21 are forced between the frame 1 and the lower edges of the end-pieces 2, sufficiently to relieve such friction. Said 15 wedges also operate as stops, to determine the degree of movement of the bar 8 rearwardly, and can be adjusted with reference to such bar by means of threaded rods 22 attached to the rear part of the frame and 20 extending through perforations in the wedges 21. On each side of said wedges the threaded portion of the rods 22 is provided with nuts 23, by means of which the wedges may be held in adjusted positions.

25 Secured to the rear face of the cross-piece 5 is a plurality of brackets 24, upon which is slidably supported a cross-bar 25, connected with which is a series of pins 26, extending forwardly through perforations in the cross-pieces 5 and 6. When the post has been formed the bar 25 is drawn forwardly by means of handles 27 at the ends thereof, causing the pins 26 to pierce the post, forming holes therein for the attachment of 30 wires. When the operation is completed, the pins 26 are returned to their former position, the board 16 swung downwardly, and the pallet 15, with the completed post thereon, removed from the machine, and set in a 35 suitable place for the material in the post to become hardened. A new pallet is then placed in position in the machine and the operation resumed.

40 The size of the pest to be produced can be

varied by raising or lowering the brackets 45 12 upon the face of the cross-piece 6 and securing them in their adjusted positions. The position of the front-board 16 can also be changed to conform to the position of such brackets and the width of pallet supported thereon, by changing the pivotal position of such board upon the extensions of the bars 4. The change in the size of the mold obviously disturbs the proportions of material furnished thereto by the action of 50 the bar 8, and by a proper adjustment of the wedges 21 the rearward movement of such bar is increased, causing the material to be once more delivered to the mold in desired proportions.

60 My machine is simple in construction and operation, and by the use thereof the posts can not only be easily and rapidly produced, but the reinforcing means will be uniformly located therein, at such points as are determined to be best suited for its efficiency and durability.

65 What I claim as my invention, and desire to secure by Letters Patent of the United States, is:

70 A machine of the character described comprising a frame, a plate located thereon, a receptacle pivoted upon the frame and located above the plate, wedges interposed between the receptacle and the frame, means 75 for moving the wedges whereby the position of the receptacle with relation to the plate is varied, a bar movably mounted upon the plate below the receptacle and a material container mounted upon the frame and located at the delivery edge of the plate.

76 In testimony whereof I affix my signature in presence of two witnesses.

EDWARD J. CONDON.
